US0D1060020S

(12) **United States Design Patent** (10) **Patent No.:** **US D1,060,020 S**
(45) **Date of Patent:** **** Feb. 4, 2025**

(54) **DRAWER SLIDE**

(71) Applicant: **CHANGSHA BAITUO IMPORT AND EXPORT CO., LTD.**, Hunan (CN)

(72) Inventor: **Bin Wang**, Hunan (CN)

(**) Term: **15 Years**

(21) Appl. No.: **29/933,267**

(22) Filed: **Mar. 19, 2024**

(51) **LOC (15) Cl.** **08-11**

(52) **U.S. Cl.**

USPC **D8/377**

(58) **Field of Classification Search**

(57) **CLAIM**

The ornamental design for a drawer slide, as shown and described.

DESCRIPTION

FIG. 1 is a front, bottom perspective view of a drawer slide, showing my new design;

FIG. 2 is a rear, top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another perspective view thereof, shown in an environment of use.

The broken lines shown in FIG. 9 are for the purpose of illustrating environmental subject matter only and form part of the claimed design.

1 Claim, 9 Drawing Sheets
